OARLOCK

Scott N. Weeks, Melrose, Mass.

Application December 17, 1934, Serial No. 757,814

2 Claims. (Cl. 9—26)

The present invention has for its general objectives an oar lock which is of sturdy construction and made up of but few parts; which truly locks the oar in the sense that slippage or loss of the oar during rowing is prevented; which permits of ready assembly with the oar handle and with oar handles of somewhat variant diameters; and which permits the oarsman to manipulate the oar with ease and with the desired universal movement, that is, with combined forward and backward and upward and downward movements.

With the foregoing and other objects in view, the present invention will now be described in detail with particular reference to the accompanying drawing, wherein,—

Figure 1 is a front elevation of an oar lock embodying the present invention.

Figure 2 is a side elevation of the same.

Figure 3 is a section on the line 3—3 of Figure 1.

Figure 4 is a fragmentary section on the line 4—4 of Figure 1.

Figure 5 illustrates in perspective the lock installed on a row boat.

As shown in Figure 1, the lock comprises a yoke 10 serving as a mounting or bracket for a ring structure 11 wherein the oar handle is designed to be received and which is adapted to be locked tightly to the handle. The yoke includes the arms 10a and 10b projecting from a stud 10c which is free to turn in a bushing or sleeve 9 through which it passes. The bushing 9 projects downwardly from a base plate 8 adapted to be secured to the gunwale 7 of a boat, as shown in Figure 5. The bushing 9 may enter downwardly through and out of a suitable opening formed in the gunwale, the lower end portion of the stud 10c projecting beyond the lower end of the bushing and preferably being provided with an aperture 6 through which a ring 5 or equivalent element may be inserted for the purpose of keeping the yoke fast to the plate while permitting turning movement of the yoke and, accordingly, forward and backward movement of an oar.

The ring structure 11 has pins 12 and 13 projecting outwardly on opposite sides substantially midway thereof. One of the pins 12 is pivotally received in a recess 14 in the arm 10a of the yoke; and the other pin 13 is pivotally received in the lower end portion of a vertical groove 15 in the arm 10b of the yoke. The groove 15 extends and progressively increases in depth from the upper end to an intermediate point of the arm 10b, the recess 14 in the arm 10a being substan-

tially opposite to the base or ledge 15c of the groove 15 on which the pin 13 rests. The pins 12 and 13 of the ring structure are thus received in the arms of the yoke so as to permit rocking movement thereof and, accordingly, up-and-down movement of an oar while at the same time permitting ready demounting of the ring structure from the yoke. Thus, the pin 13 is capable of being moved or withdrawn upwardly through the groove 15 and out of its upper end while withdrawal of the pin 12 from the recess 14 is simultaneously being effected so as to effect complete disassembly of the ring structure from the yoke. Normally, however, an upward movement of the pin 13 is prevented by a suitable removable stop element, for instance, a screw 16 threaded through the arm 10b with its shank slightly clearing above the pin 13 and its head 17, shown knurled, outwardly of the arm.

When the ring structure is disassembled from the yoke, it may be readily locked to an oar handle, although, of course, it may be so locked in place even while mounted on the yoke. The ring structure includes a substantially central upper arcuate locking piece 18 of an internal curvature preferably corresponding substantially to the internal curvature of the rest of the ring structure. The ring structure additionally includes an upper enlarged or boss portion 19 recessed at 20 to receive therein the locking piece 18. A screw 21 is shown threaded through the upper ring portion 19 and having an unthreaded lower end portion 21a to which the locking piece 18 is rotatably secured. Thus, as appears best in Figure 1, the unthreaded portion 21a of the screw 21 passes through the piece 18 and is equipped with an end flange 21b free to glide over a locally countersunk lower surface 22 in such piece, such flange preventing disengagement of the screw 21 from such piece as turning movement of the screw causes upward or downward movement of such piece. The upper or head end portion of the screw 21 projects beyond the upper ring portion 19 and is shown with a knurled head 23. The recess 20 is preferably of such depth that when the piece 18 is fully retracted within the recess, the internal surface of such piece constitutes essentially a continuation of the internal surface of the rest of the ring structure.

In order to prevent undesirable turning movement or dislocation of the piece 18 as it is being moved vertically by turning of the screw 21, the side walls of the recess 20 are preferably provided with vertical ribs 24 fitting into complementary

grooves or ways 25 in the side walls of the locking piece 18, such piece thus being free to undergo vertical translation while at the same time being held against rotation.

- 5 An advantage of the oar lock of the present invention is adapted for use with oars having handles of somewhat variant diameters, since the locking piece 18 is capable of being clamped tightly onto oar handles of a diameter materially 10 smaller than the internal diameter of the ring structure even though the ring structure is designed primarily to receive oar handles of a diameter only slightly less than its internal diameter. The ring structure is so easily demountable 15 from the yoke that upon finishing rowing, the oarsman can quickly demount the ring structure while locked to the oar handle from the yoke and place the same in the boat.

I claim:

- 20 1. In an oar lock, the combination with a yoke and a base in which said yoke is free to turn and thus to permit forward and backward movement of an oar, of a ring structure adapted to be locked to an oar handle and demountably and 25 rockably secured to said yoke with rockability permitting up-and-down movement of an oar, said ring structure including an upper arcuate locking piece of an internal curvature corresponding substantially to the internal curvature 30 of the rest of the ring structure, an upper ring portion recessed to receive therein said locking piece, and a screw threaded through said upper ring portion and having an unthreaded lower end portion to which said locking piece is rotatably 35 secured, said screw being rotatable to cause vertical and inward movement of said locking piece and to clamp it onto the handle of an oar inserted through said ring structure, the side walls of said recessed upper ring portion being 40 equipped with vertical ribs fitting into comple-

mental recesses in said locking piece to prevent turning movement of said locking piece while said locking piece is being moved vertically.

2. In an oar lock, the combination with a yoke at least one arm of which contains a groove extending and progressively increasing in depth from an upper end to an intermediate point thereof and the other arm of which contains a recess opposite to the base of said groove, and a base in which said yoke is free to turn and thus to permit forward and backward movement of an oar, of a ring structure adapted to be locked to an oar handle and demountably secured to said yoke, said ring structure including pins projecting from opposite sides thereof, one of said pins being pivotally received in said grooved arm at the base of said groove and the other being pivotally received in the recess of said recessed arm so as to permit rocking movement of said ring structure and up-and-down movement of an 20 oar, said pin received in said grooved arm being capable of being moved upwardly through said groove and out of its upper end while withdrawal of the pin from said recessed arm is being effected; said ring structure further including an upper arcuate locking piece of an internal curvature substantially corresponding to the internal curvature of the rest of the ring structure, an upper ring portion recessed to receive therein said locking piece, and a screw threaded through said upper ring portion and having an unthreaded lower end portion to which said locking piece is rotatably secured, said screw being rotatable to cause vertical and inward movement of said locking piece and to clamp it onto the handle of an 30 oar inserted through said ring structure; and a removable stop element normally preventing an upward movement of the pin in said grooved arm.
